9 Claims. (Cl. 242—43)

The invention relates to a device for conducting the thread for winding machines or the like in which the thread being wound is moved to and fro by means of grooves formed on a cylinder or drum, the grooves crossing each other at certain points and merging adjacent the ends of the cylinder to form a continuous circuit.

Such thread conducting devices for winding machines in which the thread is moved to and fro by means of two grooves in the circumference of a cylinder, said grooves either crossing or not and merging at the ends the one into the other are known in the art. In these devices, however, the preventing of the jumping over of the thread at the points of intersection from the guiding into the oppositely directed groove always presents great difficulties. In order to avoid having the thread jump at the points of intersection from the guiding groove into the oppositely directed groove, it has already been proposed to arrange in front of the cylinder which carries the guide groove a separate movable thread guide.

Such a thread guide is moved to and fro by the grooved cylinder by means of a transmission gear in accordance with the pitch of the guide groove. Besides the complicated mechanism of the second thread guide this arrangement presents the inconvenience that, owing to the necessity of the thread guide parts being moved to and fro, the running-on speed of the thread is limited. The proper operation of the device is complicated by the presence of the second movable thread guide.

An arrangement has also become known in which in front of such a grooved cylinder, a circulating additional thread guide is arranged which permits a higher running-on speed of the thread but renders the winding arrangement complicated as regards construction and operation.

In another known arrangement of this kind no additional thread guide is provided. For avoiding the reversing of the thread at the points of intersection, so-called guiding elements are arranged on the grooved cylinder, which consist of different depths of the intersecting grooves and in bevelled faces on the intermediate pieces at the points of intersection, or in that the portion of the grooves situated behind the point of intersection is displaced relative to the portion in front of this point. The thread is thereby hindered at the points of intersection, this being especially perceivable in the case of multi-thread weakly twisted yarns.

In another known construction of the grooved cylinder the arrangement of the grooved cylinders at the intersecting points is designed to avoid an additional thread guiding so that actually one groove is continuous and the opposite groove is interrupted in front of and behind the points of intersection. The re-catching of the thread behind the points of intersection is, however, difficult in such an arrangement.

In all these arrangements it is still possible that the thread may reverse its direction of movement, which may lead to faulty bobbins.

For the production of narrow bobbins these grooved cylinders are well-suited. However, the wider the groove to be produced or the greater the distance which the thread to be conducted to and fro has to travel, the more difficult will it be to shape in these arrangements the points of intersection of the groove so that an unimpeded passing of the thread through the points of intersection is ensured.

This invention relates to grooved cylinders of the two last mentioned types having thread guiding grooves in which, for instance, the guide grooves do not intersect, i. e., a groove extends continually at the points of intersection, whereas the oppositely directed groove is shallower at these points or interrupted in front and behind of the point of intersection; and this arrangement avoids the existing inconveniences by positioning in front of such a cylinder a guiding element which is not movable to and fro, for effecting an additional thread displacement in the direction of the thread travel. This guiding element consists for instance of a stationary bar which either has inclined portions, i. e., differences in height over the whole width of the grooved cylinder or is inclined in the direction of its width from both sides towards the middle. This inclined face may be curved. The guiding element may also be rectilinearly stepped. In this instance small differences in height exist only at the points of intersection of the grooves.

In cases where a guide element having inclined portions throughout its whole width is employed, one groove of the guide cylinder must be continuous, the opposite groove being, however, interrupted or of less depth in front of and behind the points of intersection. If guide elements are employed which have inclines from both sides towards the middle or which are rectilinearly stepped from both sides towards the middle and have inclines only at the points of intersection, the grooves of the guide cylinder are shaped so that the portion of the grooves from

- the middle towards the right and left respectively are continuous and the portions of these same grooves which lead backwards towards the middle are interrupted or have shallower depth.
- 5 Before the thread runs through the grooves of the guide cylinder onto the spool, it slides over the guide element arranged in front of the cylinder. If the thread is being guided by a continuous groove, it slips without resistance over the 10 incline of the guide element. If the thread reverses its direction of movement, it is conducted by a groove which has shallower depth or is interrupted in front of and behind the point of intersection. If the thread arrives at the point 15 at which the guide groove is interrupted in front of the point of intersection or if it is guided by a groove of shallower depth, it is lifted over the continuous or lower situated groove and is for a moment freely movable. The incline of the 20 guide element begins then to act and shifts the thread in the direction of the inclination of the interrupted groove. By means of the incline at the points of intersection, an additional lateral displacement is therefore imparted to the thread 25 in the direction of the incline so that it is then guided by the correct groove.

An embodiment of the invention is illustrated in the accompanying drawings by way of example in connection with the grooved cylinder 30 in which one guide groove is continuous and the other guide groove interrupted in front of and behind the point of intersection.

Fig. 1 shows in front elevation the device for guiding the thread. In this arrangement the 35 thread to be guided is conducted over a guiding element with inclination in one direction.

Fig. 2 shows the arrangement of Fig. 1 in side elevation.

Fig. 3 shows the device in which the thread 40 is conducted over a guide element which is stepped in straight lines towards the middle. The incline for conducting the thread from the interrupted groove into the groove beginning again is provided only at the points of intersection 45 of the grooves.

Fig. 4 shows the arrangement of Fig. 3 in side elevation.

Fig. 5 shows the guiding element with inclination from both sides towards the middle and in 50 curved shape.

Fig. 6 is a side elevation of Fig. 5.

Fig. 7 shows the guide element alone.

Figure 8 is a plan view of the same guide element;

55 Fig. 9 is a plan view of a similar guide element which is bent at an angle at its mid portion; and

Figure 10 is a plan view of a guide element laterally curved throughout its length.

60 The thread 2 from the reserve bobbin 1 is tensioned by the thread brake 3 and runs over the guide cylinder 4 to the spool 5, by which it is wound up. This spool 5 is driven by the rotating grooved cylinder 4 on which it bears

65 and is rotated by friction. The spool 5 may be rotated independently of the grooved cylinder 4 by a separate drive. In front of the grooved guide cylinder 4 a guide rail 6 is arranged which, as shown clearly in Figure 1 of the drawings,

70 are inclined towards one side throughout the whole length of the grooved cylinder. If desired, the guide bar may be stepped in straight line portions and have inclined surfaces only at the points at which the grooves are interrupted similar to the arrangement illustrated in Figures 3

and 4 in connection with the second embodiment of the invention. The thread 2, before it gets onto the grooved cylinder 4 slides over this guide bar 6. If the thread 2 is directly conducted by the groove 7 interrupted in front of the points of intersection, it is lifted shortly before the point of intersection of the grooves by the point of interruption and lies free. The incline of the guide bar 6 performs its function at this moment. By the thread pull the thread 2 slides over the 10 inclination and is additionally shifted in the direction of the continuation of the groove 7 after the interruption therein where it crosses the continuous groove designated by the reference numeral 9, whereby it is ensured that the thread 15 is caught again by the groove 7. With this object in view the groove 7 beginning again at 20 8 in the direction of movement of the cylinder is slightly widened. The two grooves 7 and 9 may be considered as beginning and ending at 25 the points of reversal 10 near the ends of the cylinder. When the thread 2 passes over the incline of the guide bar 6 on its return movement, it is always guided by the continuous uninterrupted guide groove 9. The inclination 20 of the guide bar is, however, so little, that the thread is not stressed during the backward movement over the same.

As already indicated, in the embodiment illustrated in Figures 3 and 4, the grooves are differently formed on each side of the middle of the cylinder. The interrupted portions of the grooves are designated 7' and the uninterrupted portions 9'. The guide bar indicated at 16 is stepped and the straight portions are connected by inclined portions which occur at the points of interruption of the groove portions 7', and which function in the same manner as the continuous sloping bar 6 of the embodiment first described, to give the thread a forward impetus 40 at these points in whatever direction the interrupted portion requires. In this case, of course, the interrupted portions 7' of the grooves both lead toward the center of the guide roller.

Considered from one standpoint, each half of 45 the cylinder in Figures 3 and 4 may be considered equivalent to the full cylinder in Figures 1 and 2, except that the interrupted and uninterrupted portions of the grooves on one side lead in the opposite directions. On this account 50 the inclined portions of the stationary guide bar 16 slope in the opposite direction on opposite sides of the mid-point.

Another modification of the guide member is illustrated in Figures 5, 6, 7, and 8, wherein the 55 guide bar 26 is provided with continually curved surfaces upon each side of the center line thereof. In Figure 9 a similar guide member 36 is shown which is provided with an angular bend at the central portion thereof. A still further modification indicated at 46 in Figure 10 comprises a similarly notched guide member which is provided with a continuous lateral curvature.

It is not necessary to make the guide element or guide rail in one piece as it may be composed 65 of several parts without departing from the invention.

From the above descriptions it will be understood that one of the grooves—namely the interrupted one—will have less thread retaining capacity than the other and may be considered typical of various kinds of grooves of diminished guiding ability, such as those described in the early paragraphs of the present specification. The uninterrupted or continuous groove, of 70

course, is the one of greater thread retaining capacity, and these designations may be used in certain of the subjoined claims.

I claim:

5. 1. In a winding machine, in combination, means for supporting a spool during a winding operation, and mechanism for guiding a thread passing onto the spool, said mechanism including a revoluble cylinder having separate grooves formed therein for traversing the thread in opposite directions axially of the cylinder, one of said grooves having greater thread retaining capacity than the other, and means positioned adjacent the cylinder over which the thread passes on its way to the cylinder for urging the thread to move axially of the cylinder in a direction to follow the groove of less thread retaining capacity.

2. In a winding machine, in combination, means for supporting a spool during a winding operation, and mechanism for guiding a thread passing onto the spool, said mechanism including a revoluble cylinder having separate grooves formed therein for traversing the thread in opposite directions axially of the cylinder, one of said grooves having greater thread retaining capacity than the other, and means positioned adjacent the cylinder over which the thread passes on its way to the cylinder for urging the thread to move axially of the cylinder in a direction to follow the groove of less thread retaining capacity, said means resisting but not preventing the thread from following the groove of greater thread retaining capacity.

3. In a winding machine, in combination, means for supporting a spool during a winding operation, and mechanism for guiding a thread passing onto the spool, said mechanism including a revoluble cylinder having separate grooves formed therein for traversing the thread in opposite directions axially of the cylinder, one of said grooves having greater thread retaining capacity than the other, and a stationary guide positioned adjacent the cylinder, over which guide the thread passes on its way to the cylinder, for urging the thread to move axially of the cylinder in a direction to follow the groove of less thread retaining capacity.

4. In a winding machine, in combination, means for supporting a spool during a winding operation, and mechanism for guiding a thread passing onto the spool, said mechanism including a revoluble cylinder having separate grooves formed therein for traversing the thread in opposite directions axially of the cylinder, one of said grooves having greater thread retaining capacity than the other, and a stationary guide member positioned adjacent the cylinder, over which the thread passes on its way to the cylinder, for urging the thread to move axially of the cylinder in a direction to follow the groove of less thread retaining capacity, said guide member being coextensive in length with the groove of less thread retaining capacity.

5. The combination set forth in claim 4 in which the guide member comprises a straight uniformly sloping bar disposed angularly to the axis of the cylinder.

6. In a winding machine, in combination,

means for supporting a spool during a winding operation, and mechanism for guiding a thread passing onto the spool, said mechanism including a revoluble cylinder having a substantially helical groove formed therein for traversing the 5 thread in one direction axially of the cylinder, and another helical groove therein for traversing the thread in the opposite direction, each of said grooves having portions of greater and less thread retaining capacity, and a stationary guide 10 member positioned adjacent the cylinder, over which the thread passes on its way to the cylinder, and having spaced portions for urging the thread to follow the portions of the groove of less thread retaining capacity.

7. The combination set forth in claim 6 in which the portions of less thread retaining capacity lead toward the longitudinal mid-point of the cylinder and the stationary guide member has two thread guiding surfaces each inclined 20 from the outer ends toward the center thereof to urge the thread to follow said portions of the grooves.

8. In a winding machine, in combination, means for supporting a spool during a winding 25 operation, and mechanism for guiding a thread passing onto the spool, said mechanism including a revoluble cylinder having substantially helical grooves formed in the surface thereof, the convolutions of said grooves leading in opposite 30 directions axially of the cylinder and intersecting at a plurality of points therealong, one of said grooves being interrupted at certain of said points of intersection and the other continuous, and a stationary guide member positioned adjacent 35 said cylinder, over which the thread passes on its way to the cylinder, said guide having a stepped thread contacting surface with spaced inclined portions thereon, each of said inclined portions disposed opposite one of said points of 40 intersection on the cylinder whereby the thread is urged to move in the direction to follow the continuations of the interrupted grooves.

9. In a winding machine, in combination, means for supporting a spool during a winding 45 operation, and mechanism for guiding a thread passing onto the spool, said mechanism including a revoluble cylinder having substantially helical grooves formed in the surface thereof, the convolutions of said grooves leading in opposite 50 directions axially of the cylinder and intersecting at a plurality of points therealong, one of said grooves being interrupted at certain of said points of intersection and the other continuous, the reverse condition prevailing at certain other 55 of said points of intersection, and a stationary guide member positioned adjacent said cylinder, over which the thread passes on its way to the cylinder, said guide having a stepped thread contacting surface with spaced inclined portions 60 thereon, each of said inclined portions disposed opposite one of said points of intersection on the cylinder and sloping in the direction of lead of the interrupted groove portion at said point, whereby the thread is urged to move in the direction to follow the continuations of the interrupted grooves.

HEINRICH DERSEN.
